UNITED STATES PATENT OFFICE

PHILIP A. EYRICK, OF CAMBRIDGE, MASSACHUSETTS, ASSIGNOR TO NATIONAL COMPANY, INC., OF MALDEN, MASSACHUSETTS, A CORPORATION OF MASSACHUSETTS

ELECTRIC TERMINAL CLIP

Application filed June 19, 1929. Serial No. 372,001.

My invention aims to provide improvements in electric terminal clips.

In the drawing which illustrates a preferred embodiment of my invention:—

5 Figure 1 is a perspective view of a terminal clip as it appears when connecting a conductor wire to the "grid" contact of a vacuum tube;

10 Fig. 2 is a side elevation of the clip; and Fig. 3 is a plan view of the clip.

15 Referring now to the embodiment of my invention illustrated by the drawing, I have shown a so-called "grid clip" which is particularly adapted for making an electrical contact between a conductor wire and the "grid" contact located on top of a vacuum tube used in wireless and like apparatus. It is to be understood, however, that a clip coming within the scope of my invention may 20 have other equally important uses as an electric terminal clip.

The particular clip selected for illustrative purposes is formed from a single piece of sheet metal and has a substantially continuous yieldable sleeve portion 1. The ends of the metal extend from the sleeve portion at one side (Fig. 3) to provide a pair of finger pieces 2 and 3. The finger piece 2 is provided with a slot 4 which extends part way 25 into the sleeve, as shown in Fig. 2. The finger 3 is about the same width as the slot 4 through which it passes and has its end bent in substantial parallelism with the finger 2 (Fig. 3) and in spaced relation thereto so that 30 when the fingers are squeezed toward each other the sleeve will be expanded.

35 Any form of means may be carried by the finger 2 for receiving and holding the wire conductor 5, but I prefer to provide an integral U-shaped extension 6. Thus the wire 5 may be soldered in place between the leg portions of the U and the legs may then be bent to hold the wire in place in the usual manner well known to those skilled in the art.

40 The device which I have described is readily attachable to and detachable from the contact 7 secured to the top of the vacuum tube 8 (only a part of which is shown) by merely pressing the two finger pieces 2 and 3 toward each other to expand and enlarge the diameter

of the sleeve 1. When the finger pieces are released the sleeve contracts and makes a gripping engagement with the contact member.

The device illustrated and described is simple, inexpensive, durable and may be easily 55 and quickly applied. When attached to a contact member it makes a firm contact with a substantial area of the contact member, thereby affording a very desirable electrical connection.

60 While I have illustrated and described a preferred embodiment of my invention, I do not wish to be limited thereby, because the scope of my invention is best defined in the following claims.

I claim:

1. An electric terminal clip pressed from sheet metal and having a substantially continuous cylinder-like yieldable sleeve of substantial length and being in the form of a circular loop for substantially continuous contact with a contact member, and a pair of spaced finger pieces connected to said sleeve, one of said finger pieces having a slot, and the other finger piece having its end extending through said slot thereby to provide squeeze-operated means whereby when the finger pieces are pressed toward each other the sleeve will be expanded to permit engagement with and disengagement from a contact 70 member.

2. A one-piece electric terminal clip formed from a strip of sheet metal and having a cylindrical sleeve portion 1 formed in the said strip of sheet metal, a finger piece 2 formed by one end of said strip and extending from the sleeve and having a slot 4, a second finger piece 3 formed from the other end of said strip having its free end extending through said slot and bent in substantial parallelism to the finger 2 and a U-shaped portion formed at the end of the finger 2 all as and for the purposes illustrated and described.

90 In testimony whereof, I have signed my name to this specification.

95 PHILIP A. EYRICK.
